UNITED STATES PATENT OFFICE.

WILLIAM R. ECKE, OF EMSWORTH, PENNSYLVANIA, ASSIGNOR TO JAMES H. MATHEWS & COMPANY, OF PITTSBURGH, PENNSYLVANIA, A CORPORATION OF PENNSYLVANIA.

EMBOSSING AND SHEARING MACHINE.

Application filed May 7, 1925. Serial No. 28,605.

To all whom it may concern:

Be it known that I, WILLIAM R. ECKE, residing at Emsworth, in the county of Allegheny and State of Pennsylvania, a citizen of the United States, have invented or discovered certain new and useful Improvements in Embossing and Shearing Machines, of which improvements the following is a specification.

10 My invention relates to improvements in machinery for forming from an indefinite length of sheet material, ordinarily metal, a succession of duplicate plates of desired size and contour and bearing legible characters embossed upon them. Such plates have very extended use as labels for material of various sorts,—wire fencing, for example, fabricated and packaged for the market. The improvements in which my invention is 15 found enable me to produce from the machine plates which are superior in the accuracy of their shaping and in the neatness and uniformity of their appearance.

20 Machines embodying my invention are illustrated in the accompanying drawings. Fig. I is a view in longitudinal section of one such machine, the plane of section being that indicated by the line I—I, Fig. II. Fig. II is a view in transverse section, on the plane indicated at II—II, Fig. I. Fig. III is a view in horizontal section, on the plane indicated at III—III, Fig. I. Fig. IV is a diagrammatic view, showing in plan a strip of material which, under machine operation, is 25 in course of fabrication into a succession of plates. Fig. V is a view corresponding to Fig. I and illustrating another machine which, differing in detail, still is an embodiment of my invention. Fig. VI is a view corresponding to Fig. IV, and illustrating fabrication in the machine of Fig. V.

30 Referring first to the machine of Figs. I—III, it includes a suitable bed or anvil 1 and a cooperating reciprocating head 2. The bed carries a die block 3 and a shear block 4, spaced at a proper interval to achieve ends which will become plain as the description continues. The head carries a pressure block 5. A sub-press is provided, which includes a 35 reciprocating head 6 carrying a shear block 7.

The die block 3 is adapted to receive and carry a collocation 31 of replaceable and in-

terchangeable embossing dies. This ordinarily will be assembled in a chase and the 55 chase made removable and replaceable as an entity. The pressure block 5 which cooperates with the dies so carried to effect the embossing of the sheet material is formed of suitable yielding material, suitably shaped. 60 Ordinarily it is a plain-faced block of wood.

The bed of the machine is shown to be recessed at 41, to afford escape for so much of the material as is sheared away in the forming of the plates. The shear block 4 is 65 perforate at 42, and the shear block 7 which cooperates with block 4 is equipped with columnar shear blades 72. Thus the shear in the embodiment presented has the character of a punch. A stripper plate 43 overhangs 70 shear block 4, as is usual in such machinery.

The reciprocating head 6 of the sub-press is normally held by springs 61 in raised position; and, in addition, stops 62 may be provided, rising from bed 1, to limit the head 6 75 in its upward range. The head 2 and the head 6 are so arranged that the head 2 on its down stroke abuts upon head 6 from above, and, pressing upon it from above, drives it downward in simultaneous stroke. 80

The shear members may take such particular shape as may be desired. Their shape in this particular instance is sufficiently indicated in Fig. III, and the consequent shape given to the sheared article is indicated in 85 Fig. IV.

A strip of material α is carried, by suitable feed mechanism, not shown, in direction from right to left, as seen in Fig. I, and is intermittently brought to rest after advance through a definite and predetermined interval. The advance of the material and the descent of the head 2 are alternate, co-ordinated movements.

90 The material α having been advanced to proper position above bed 1, comes to rest. The head descends, and two operations are performed upon it: the web of the strip, borne upon from above by pressure block 5, is embossed upon the embossing dies 31, and 100 the advance end of the strip is sheared to shape. The head then rises, the material is fed forward through the predetermined interval and then stops again, and the head descends again. On the second descent one 105 finished plate is sheared free, and a suc-

ceeding plate is shaped at its advance end, and is embossed with the desired characters. Referring to Fig. IV, the first descent of the head embosses the characters m , and 5 cuts the edge s and the slot x ; the second descent embosses the character n , and cuts the edges t , and the slots y . The second descent of the head then completes the article A, and each succeeding descent of the 10 head (with coordinated feed of the strip) completes a like article.

Invention lies in the provision of a sub-press whose reciprocating head 6 is carried downward by impingement upon it from above of the main head 2. When the pressure block 5 and the shear member 7 are mounted upon a single head, difficulties arise. The pressure requisite to emboss is greater than that requisite to shear; the 20 varying arrangement of the embossing dies 31 gives rise to tipping strains upon the head 2. Furthermore, it is impossible to center the strains at all times in the line of the applied force. In consequence of such 25 conditions a shear borne in rigid union with pressure block 5 is apt to be dislocated somewhat, and irregularly dislocated, with respect to its companion shear. The consequences and results are ragged work and 30 worn machinery. By adopting the sub-press these difficulties are avoided, and by rendering the head of the sub-press subject to the head of the companion press, so that the two heads descend in unison, and yet 35 with the capacity of independent lateral adjustment, a simple and effective avoidance of difficulty is achieved. It will be observed of head 6 that the accuracy of its position on down stroke will not be disturbed by any 40 tipping or minor displacement of head 2.

In Fig. V a machine embodying the invention is shown, and in it the idea of driving the head of the sub-press by impingement upon it from above of the power-driven head of the main press, is elaborated somewhat. Here are found two sub-presses, 45 with two heads 6^a and 6^b, both driven by the head 2 of the main press. These two sub-press heads carry shear members 7^a and 7^b. Correspondingly, the bed 1 is provided 50 with cooperating shear blocks 4^a and 4^b.

Comparison of Fig. VI with Fig. V will 55 show that in this case each article produced is acted on by three successive reciprocations of the compound head: The first embosses the web of the still uncut strip, as indicated at n , Fig. VI; the second downward reciprocation of the head (the blank having meanwhile advanced one step) 60 punches out the slots; and the third reciprocation (after a second step forward)

punches the finished article A out of the strip.

I claim as my invention:

1. In an embossing and shearing machine 65 the combination of a bed, a plunger reciprocable with respect to the bed, a second plunger reciprocable with respect to the bed and adapted to be engaged by the first plunger in its descent and carried toward the bed, a pair of cooperating embossing instrumentalities borne one by the bed and the other by one of the two plungers, and a pair of cooperating shearing instrumentalities borne one by the bed and the other by the 70 other plunger.

2. In an embossing and shearing machine 75 the combination of a bed, a plunger reciprocable with respect to the bed, a second plunger reciprocable with respect to the bed and arranged beneath the first plunger, a pressure block borne by one of said plungers and a shear member borne by the other plunger, and cooperating embossing die and shear member borne by the bed. 80

3. In an embossing and shearing machine 85 the combination of a bed, a plunger reciprocable with respect to the bed and equipped with a pressure block, a second plunger arranged beneath and subject to the first plunger in its descent and equipped with a shear member, said bed being equipped with a cooperating embossing die and shear member. 90

4. In a machine for embossing and shearing the combination of a suitably supported stationary shear block, a spring supported head equipped with a companion shear block adapted to be closed against spring tension upon the shear block first named, a suitably supported embossing die and a reciprocable head equipped with a pressure block, the head last named in its reciprocation adapted to bring its pressure block to cooperation with said embossing die, and adapted further to shirt the head first named and to bring the shear block borne thereby into cooperation with the shear block first named. 95

5. In an embossing and shearing machine 100 the combination of a bed, a removable and replaceable chase borne by said bed and adapted to carry a collocation of embossing dies, a shear member borne by said bed, two plungers reciprocable with respect to said bed, one of said plungers being driven by 105 the other in its descent to the bed, one of said plungers being provided with a shear member and the other with a pressure block. 110

In testimony whereof I have hereunto set my hand.

WILLIAM R. ECKE.
